WRINGER MOP

Leslie B. Hoffman, Chicago, Ill., assignor to Dayless Mfg. Co., Inc., Chicago, Ill., a corporation of Illinois

Application May 18, 1950, Serial No. 162,680

1 Claim. (Cl. 15—119)

1

The invention relates to improvements in mops, and is more particularly concerned with a novel mop construction embodying manually actuatable wringer means for the mopping element.

An object of the present invention is to provide a novelly constructed wringer mop of the character described.

Another object of the invention is to provide a mop with a novelly mounted mop element and a novelly constructed wringer element.

Another object is to provide a wringer mop with a novel two-piece housing for carrying the wringer rollers.

Another object is to provide a durable, rigidly constructed wringer mop of a kind that may be manufactured inexpensively.

Other objects of the invention will appear from the following description and accompanying drawings and will be pointed out in the annexed claim.

In the accompanying drawings there has been disclosed a structure designed to carry out the various objects of the invention, but it is to be understood that the invention is not confined to the exact features shown as various changes may be made within the scope of the claim which follows.

In the drawings:

Fig. 1 is an elevational view of a mop structure embodying features of the present invention.

Fig. 2 is an end elevational view of the mop shown in Fig. 1, showing a portion of the handle and actuating links broken away.

Fig. 3 is a transverse sectional view, taken substantially on line 3—3 of Fig. 1.

Referring to the accompanying drawings, the mop includes a conventional elongated handle 11 having a bell-shaped housing 12 firmly mounted on one end. The housing 12 is fabricated from two like halves, each formed from suitable sheet material such as steel or aluminum. Each housing half includes one-half of a socket 13 having abutting side flanges 14 adapted to be secured together, as by screws 15, so as to firmly secure the end of the handle in the socket.

The body portion of the housing 12 is, as aforesaid, substantially bell-shaped and it includes an arched wall 16 and end walls 17. The end walls consist substantially of end flanges adapted to define an inverted U-shaped end wall opening 18 between their opposed edges. The lower margins of the side wall 16 are preferably offset outwardly, as at 19, for a purpose to become apparent as the description proceeds.

2

A pair of built up rollers is mounted in the offset end portions of the bell-shaped housing 12. As shown, each of the rollers 21 consists of a plurality of axially aligned sections, one of which is located between the end walls or flanges 17 of the bell-shaped housing and the other sections of which are disposed outwardly thereof. The sections of each roller are mounted upon common axes 22 journaled in the respective end flanges 17 and, as is best shown in Fig. 3, the wall offsets 19 afford clearance for said rollers within the housing 12.

A channel 23 is arranged within the bell-shaped housing 12 and extends beyond each end thereof. This channel has a length corresponding substantially to the length of the rollers 21 and it has its open side 24 disposed downwardly, as is best shown in Fig. 3. The channel is provided to constitute mounting means for a mopping element 25 which, in the present instance, is fabricated from suitable sponge rubber, or like resilient material, so that when the channel and mopping element 25 are in the position shown in Fig. 2 the portion of the mopping element extending beyond the rollers 21 will flare outwardly.

Means is provided whereby the channel and mopping element may be drawn upwardly into the bell-shaped housing 12 into a position substantially as shown in Fig. 3. When the mopping element is in this position, its normally flared portion is constricted between the rollers 21 whereby excessive water contained therein is wrung out of the mopping element. The means provided for drawing the channel 23 and its mopping element 25 into the bell-shaped housing 12 consists of a lever 27 and a pair of connecting links 28.

The lever 27 may be of any conventional construction. However, it is preferred that it be fashioned from strap stock bent substantially U-shaped and having the free ends of its side portions journaled to the handle 11 as by a pivot 29. The lever is pivoted to the handle 11 at a considerable distance from the end carrying the bell-shaped housing 12. This positioning of the lever facilitates manipulation of the wringer mop in that it is unnecessary for the user thereof to bend over so as to reach any operating mechanism which might be closely associated with or formed as a part of the bell-shaped housing or its mounting.

The links 28 are pivotally connected at their upper ends to the lever 27, as by rivets 31, and their lower ends are each pivotally secured at 32 to one of a pair of ears 33 formed on the ends.

of a strap 34 inserted into the channel 23. Upon referring to Fig. 3, it will be noted that the ears 33 extend through slots 35 in the channel 23, thus constituting relatively firm mounting means for said ears.

It should be obvious at this time that when the mopping element is drawn upwardly between the rollers 21 in a wringing operation the inherent yieldability of the mopping element is such as to automatically tend to return the mopping element and actuating parts to their initial positions shown in Fig. 2.

Although an exemplary embodiment of the mop construction has been shown in the accompanying drawings and described in detail in the foregoing specification, it should be understood that the invention may embody modifications in its details of construction without departing from the spirit of the invention or the scope of the appended claim.

I claim:

A mop comprising a handle, a rigid bell-shaped housing carried by the handle, said housing being fabricated from two like halves each including matching portions defining a socket to receive

10
15

the handle, end walls on the housing having aligned U-shaped openings therein, rollers in and extending beyond the end walls of said housing on each side of the U-shaped openings, a channel arranged in the housing and projecting through the end wall openings, a sponge carried by the channel and extending outwardly between the rollers, a lever mounted directly on the handle, and links extending through openings in the housing for connecting the lever with the channel, said lever and links providing mounting and actuating means for the channel whereby the channel can be moved to draw the sponge inwardly between the rollers.

LESLIE B. HOFFMAN.
